(57) **CLAIM**

The ornamental design for a portable OTG anti-counterfeit scanner, as shown and described.

DESCRIPTION

FIG. 1 is a top, front, right side perspective view of a portable OTG anti-counterfeit scanner, showing our new design;

FIG. 2 is a top plan view thereof, the bottom plan view being a mirror image thereof;

FIG. 3 is a front elevational view thereof;

FIG. 4 is a rear elevational view thereof; and,

FIG. 5 is a left side elevational view thereof, the right side elevational view being a mirror image thereof.

The broken lines represent environmental structure and form no part of the claimed design.
